United States Patent Office.

HENRY JARECKI AND CHARLES JARECKI, OF ERIE, PENNSYLVANIA.

Letters Patent No. 67,551, dated August 6, 1867.

IMPROVEMENT IN STEAM-ENGINE LUBRICATORS.

The Schedule referred to in these Letters Patent and making part of the same.

TO ALL WHOM IT MAY CONCERN:

Be it known that we, HENRY JARECKI and CHARLES JARECKI, of Erie, in the county of Erie, and State of Pennsylvania, have invented a new and improved Lubricator; and we do hereby declare that the following is a full, clear, and exact description thereof, which will enable others skilled in the art to make and use the same, reference being had to the accompanying drawing, forming part of this specification.

This invention consists in a new and improved arrangement of parts whereby the oil is filtered or strained as it enters the reservoir or chamber of the lubricator, and whereby the quantity of oil to be discharged is governed or controlled by a plunger and valve, as will be hereinafter described.

The drawing represents a vertical central section of the lubricator, showing plainly the parts of which it is composed, and the manner in which they are arranged. A represents the shell of the lubricator, which is formed of several pieces, and screwed together as seen in the drawing. B is the reservoir. C is a cap on the reservoir. D is a strainer, which is secured in the reservoir by the cap C. E is the plunger. F is a valve, which has its seat in the bottom of the globe G. The lubricator is attached to a steam engine by the part H, which is screwed into the cylinder-head. This part has a chamber, a, which contains a spiral spring, which bears up against the valve F with a constant pressure. The upper portion of the globe G extends up into the reservoir B, with lateral holes through it, as seen in the drawing, for the passage of the oil. As the oil is poured into the reservoir, it passes through the strainer D, where it is purified of foreign substances. Sediment may settle in the bottom of the reservoir, around the neck of the globe G, from which it may be removed without passing through the tube into the cylinder.

To operate the lubricator, the plunger is raised, so that the oil will descend into the tube in the globe G, when by pushing down the plunger the valve is forced from its seat, and the oil is forced through the chamber a into the cylinder. The plunger is governed in its motion up and down by the collar e. When the plunger is drawn up, the collar will strike the cap C; when pushed down, it will strike the neck of the globe G. When the engine is running, the steam will enter the chamber a and press against the valve when the upper end of the cylinder is full of steam. When the steam is exhausted from that end, the spiral spring will keep the valve in place. It will be seen that by this arrangement oil can be forced into the cylinder, and the cylinder be lubricated at all times, whether the engine is running or standing still.

What we claim as new, and desire to secure by Letters Patent, is—

The arrangement of the strainer D with the lubricator, substantially as described.

We claim the valve F, the chamber a, and the plunger E, arranged substantially as shown and described, for the purposes set forth.

HENRY JARECKI,
CHARLES JARECKI.
